Patented Dec. 14, 1965

203,182

DYNAMOELECTRIC MACHINE

Charles W. Otto, De Kalb, Ill., assignor to General Electric Company, a corporation of New York

Filed July 26, 1963, Ser. No. 75,992

Term of patent 14 years

(Cl. D26—5)

Fig. 1.

Fig. 2.

Fig. 3.

FIG. 1 is a perspective view of a dynamoelectric machine employing the new design;

FIG. 2 is an end elevational view as seen from the left of FIG. 1; and

FIG. 3 is a side or rear elevational view as seen from the left of FIG. 1.

The end frame of the dynamoelectric machine not shown in its entirety has substantially the same appearance as the end frame illustrated in FIGURES 1 and 2.

The dominant features of the design reside in the portions shown in full lines.

I claim:

The ornamental design for a dynamoelectric machine, substantially as shown and described.
